UNITED STATES PATENT OFFICE.

CHARLES A. J. GALLET, OF PARIS, FRANCE, ASSIGNOR TO PARFUMERIE ROGER ET GALLET, SOCIÉTÉ ANONYME, OF PARIS, FRANCE, A CORPORATION OF FRANCE.

DESIGN FOR BOX-COVER PAPER.

Application filed April 19, 1926. Serial No. 17,334. Term of patent 14 years.

To all whom it may concern:

Be it known that I, CHARLES A. J. GALLET, a citizen of France, residing at Paris, France, have invented a new, original, and ornamental Design for Box-Cover Paper, of which the following is a specification, reference being had to the accompanying drawing, forming part thereof.

The figure is a plan view of a piece of box cover paper showing my new design.

I claim:

The ornamental design for box cover paper, as shown.

CHARLES A. J. GALLET.
